UNITED STATES PATENT OFFICE.

CHARLES E. HUTCHINGS, OF ROCHESTER, NEW YORK, ASSIGNOR TO EASTMAN KODAK COMPANY, OF ROCHESTER, NEW YORK, A CORPORATION OF NEW YORK.

CAMERA BELLOWS.

Application filed June 28, 1923. Serial No. 648,360.

To all whom it may concern:

Be it known that I, CHARLES E. HUTCHINGS, a citizen of the United States of America, residing at Rochester, in the county of Monroe and State of New York, have invented certain new and useful Improvements in Camera Bellows, of which the following is a full, clear, and exact specification.

10 This invention relates to photography and more particularly to bellows for compact folding cameras. It has for its object to provide a bellows structure with which a camera bellows can be made 15 having portions of wall areas of different thicknesses; to provide a reinforcing system of strips which can be used in a bellows as above described; to provide a bellows structure in which certain folds may be made 20 thinner than certain other folds; to provide a bellows structure which includes the necessary reinforcing strips for retaining the shape of the bellows and for guides in making the bellows, and other objects 25 will appear in the following specification, the novel features being pointed out in the claims at the end thereof.

Modern cameras, particularly the miniature cameras taking small pictures, have 30 been made very compact, and the parts give very little clearance when in a closed or folded position. In such cameras the bellows have given the greatest difficulty owing to the non-uniformity of the thin leather 35 skivings used. In some camera bellows, leather tolerance has been small, for instance, in $2\frac{1}{4} \times 3\frac{1}{4}$ size of certain models, it is required that the leather come between .004 and .007 of an inch in thickness. 40 Such thin leather is liable to be porous making it hard to properly light proof the bellows. To be satisfactory a bellows should have a light proof lining, some reinforcing strips and a leather covering.

45 It has also been the custom to place heavy paper reinforcing strips on a blank, usually the lining material, before folding; a machine for cutting and placing such strips being shown and fully described in 50 U. S. Patent No. 981,200 for formation of an article and its application to another article, issued January 10th, 1911, to R. Kroedel. These paper strips on each fold

form guides for folding in making the bellows, (which is done by hand) and also 55 serve as reinforcing strips to prevent the bellows from collapsing causing it to retain its shape and to fold in the proper places. Each paper strip may be .009 of an 60 inch thick, and this added to the .005 of an inch thick lining, and the .007 of an inch thick leather makes the average bellows layer approximately .021 of an inch thick. It can readily be seen that several folds of 65 the bellows pile up to a considerable thickness.

My invention has to do particularly with reducing the thickness of the bellows folds, and at the same time increasing the leather thickness. It is also directed particularly 70 to reducing the thickness of certain areas of the bellows wall, where, because of the construction of the camera, the bellows folds should be of a minimum thickness.

Coming now to the drawings, wherein 75 like reference characters denote like parts throughout:

Fig. 1 is a blank from which the bellows is made;

Fig. 2 is a section of certain parts of a 80 typically thin camera, all parts being on an enlarged scale;

Fig. 3 shows in perspective the corner of my bellows; and

Fig. 4 shows half of a bellows blank reinforced 85 in accordance with, and illustrating, one form of my invention.

A bellows B is made from a blank 1 which may be cut as shown in Fig. 1 with similar sides 2, and a similar top and bottom 3, having an overlapping flap 4 of any desired shape. The bellows sections are folded on dashed lines 5 and the flap upon a dashed and dotted line 6.

It is customary to cut out a blank as 95 shown in Fig. 1 of the lining material, which may be of light proof rubberized material known commercially as camera cloth, upon which are pasted the reinforcing side strips 11 and 13 and top and bottom strips 14 and 16. Referring to Fig. 4 it will be seen that toward the large 100 end 9 of the sides (one shown) certain folds 12 do not have paper strips, and that certain strips 13 alternate with these strips 105 12. So also on the top and bottom parts

3, certain folds 15 omit the paper strips and are alternated with the reinforcing strips 16. Strips 16 are in staggered relation with strips 13. For this reason there is, when the bellows is completed, at least one reinforcing strip for each fold. After the reinforcing strips are in place, a leather blank L of the same shape and size as the lining material, is pasted over the reinforced lining.

The number of reinforcing strips is determined by the structure of the camera in which it is to be used. For example, in Fig. 2, the camera consists in a back 20 removable from a body 21, into which a lens carriage 23 may be slid by handles 24 to the folded position shown. A lens board 28 supports upon pivot 27 a finder 26. In this camera the closest fit between the camera parts, occurs between the lens carriage 23 and bellows frame 30, and between the rear end of finder 26 and the bellows frame 30. In this camera the restricted bellows area should be at the large end of the bellows, where the folds come opposite the smallest camera clearance. The bellows should, therefore, be made to fold in a minimum space at these points. Consequently the reinforcing layout shown in Fig. 4 is used. Obviously the location of the reinforcing strips may be altered to suit the particular design of camera. The bellows area which lies in the restricted region of a camera being made thin by omitting the reinforcing strips as above described.

I have found that alternate strips in staggered relation can be used without altering the durability of the bellows and that such a bellows can be as readily cut out and assembled as the entirely reinforced bellows. This structure permits a thinner bellows with heavier leather than could be heretofore used, and also allows the use of leather having a larger variation in thickness throughout, thus effecting a very substantial saving.

Moreover the bellows can be made of much stouter materials than heretofore because in the restricted areas the bellows can be made as thin, within certain limits, as desired.

I am aware that many changes can be made without departing from the scope of my invention and I contemplate as included in my invention all such changes as may come within the terms of the appended claims.

Having thus described my invention, what I claim as new and desire to secure by Letters Patent is:

60 1. A camera bellows having a series of folds, the folds of certain areas of the bellows differing in thickness from the folds of certain other areas.

65 2. A camera bellows having a series of folds of different thicknesses.

3. A camera bellows having a series of folds, some of the folds being of less thickness than others.

4. A camera bellows having a series of reinforcing strips included in the bellows walls and spaced in a definite relation, the spacing of certain strips being different from the spacing of the remaining strips.

5. A camera bellows having a series of reinforcing strips included in the bellows folds, some of the folds having two reinforcing strips, one on each side, and other folds having one reinforcing strip only.

6. A camera bellows having two pairs of similar sides, folds included in the sides, certain folds of each of the pairs of sides having two reinforcing strips, certain other folds of each of the pairs of sides having one reinforcing strip, the last mentioned reinforcing strips on one pair of similar sides being staggered in relation to the reinforcing strips of the other pair of similar sides.

7. In a folding camera, the combination with a bellows, of parts of the camera adapted to engage both ends of the bellows, parts of the camera lying close to each other when the camera is folded thus forming a restricted area with certain areas of the bellows walls lying in the restricted area, the area of the bellows walls lying in the restricted area being of less thickness than the remaining area of the bellows walls.

8. In a folding camera, the combination with a bellows, of parts of the camera adapted to engage both ends of the bellows, parts of the camera lying close to each other when the camera is folded thus forming a restricted area with certain areas of the bellows walls lying in the restricted area, a plurality of folds in the bellows walls, reinforcing strips in the folds, alternate walls of the folds being unreinforced in that area of the bellows which lies in the restricted area.

9. In a folding camera, the combination with a camera body, of a lens-carrying structure slideable into and out of the body, parts of the lens-carrying structure and parts of the body supporting a bellows, the lens-carrying structure and the body of the camera having parts lying close to each other when the camera is folded forming a restricted area, the bellows when folded having portions adapted to lie in the restricted area, reinforcing strips closely spaced in the major portion of the bellows and widely spaced in that portion of the bellows which lies in the restricted area.

10. In a folding camera, the combination with a camera body, of a lens-carrying structure slideable into and out of the body, parts of the lens-carrying structure and parts of the body supporting a bellows, the lens-carrying structure and the body of the camera having parts lying close to each other when the camera is folded forming a restricted

area, the bellows when folded having portions adapted to lie in the restricted area, a series of folds in the bellows, two reinforcing strips for each fold in the major portion of the bellows, and one reinforcing strip for each fold in that portion of the bellows lying in the restricted area, the sin-

gle reinforcing strips being arranged in staggered relation in the pairs of similar sides of the bellows.

Signed at Rochester, New York, this 26th day of June, 1923.

10
